UNITED STATES PATENT OFFICE.

EDWARD E. EKVALL, OF ELGIN, ILLINOIS, ASSIGNOR TO THE W. H. HOWELL COMPANY, OF GENEVA, ILLINOIS, A CORPORATION OF ILLINOIS.

DESIGN FOR A CHAIR.

Application filed November 19, 1928. Serial No. 28,939. Term of patent 14 years.

To all whom it may concern:

Be it known that I, EDWARD E. EKVALL, a citizen of the United States, residing at Elgin, in the county of Kane and State of Illinois, have invented a new, original, and ornamental Design for Chairs, of which the following is a specification, reference being had to the accompanying drawing forming part hereof, in which—

I claim:

The ornamental design for a chair, as shown.

E. E. EKVALL.
